INVENTOR

Sydney G. Osborne,

BY
Edgar Gate & Co.
ATTORNEY

UNITED STATES PATENT OFFICE.

SYDNEY G. OSBORNE, OF BROOKLYN, NEW YORK.

GAME DEVICE.

1,161,326.

Specification of Letters Patent.

Patented Nov. 23, 1915.

Application filed February 12, 1915. Serial No. 7,658.

To all whom it may concern:

Be it known that I, SYDNEY G. OSBORNE, a citizen of the United States, and residing at Brooklyn, in the county of Kings and State of New York, have invented certain new and useful Improvements in Game Devices, of which the following is a specification, such as will enable those skilled in the art to which it appertains to make and use the same.

This invention relates to game devices, and the object thereof is to provide an improved game or game device which will amuse and entertain both young and old and in the playing of which any amount of skill may be exercised; a further object being to provide means for playing an improved game which I call the game of Trenches; and with these and other objects in view the invention consists in a game device constructed as hereinafter described and claimed.

The invention is fully disclosed in the following specification, of which the accompanying drawing forms a part, in which the separate parts of my improvement are designated by suitable reference characters in each of the views, and in which:—

Figure 1 is a diagrammatic view of a game board which I employ; and, Figs. 2 and 3 views showing a part of two different sets of blocks or men employed in the playing of the game.

In the practice of my invention, I provide a board *a* which, as shown in the drawing, is square in form, or approximately so and on which is formed a diagram *b* consisting of a central circular field *b*² and four concentric circles *b*³, *b*⁴, *b*⁵ and *b*⁶, and the concentric circles *b*³, *b*⁴, *b*⁵ and *b*⁶ are connected at four equally spaced points by double radial lines *c* forming radial strips *c*² and at the points where the radial strips *c*² intersect or cut the circular lines *b*³, *b*⁴, *b*⁵ and *b*⁶ are circular spaces *d*, *d*², *d*³ and *d*⁴, and the circular spaces *d*², *d*³ and *d*⁴ are provided each with the numeral "2", but the circular spaces *d* at the inner ends of the strips *c*² are not provided with numerals. The concentric circles *b*⁴, *b*⁵ and *b*⁶ are provided at diametrically opposite points and midway between two of the radial strips *c*² with radially arranged circles *e*, *e*² and *e*³ in which are placed the numeral "1," and said circles *b*⁴ and *b*⁵ are also provided at diametrically opposite points and between the other two

radial strips *c*² with radially arranged circles *f*, *f*² and *f*³ in which are placed the numeral "3." The circles *b*⁴, *b*⁵ and *b*⁶, in the form shown, are divided into separate segments or arc-shaped portions *b*⁷, *b*⁸ and *b*⁹, four of which are employed, and each of which in the playing of the game constitutes a "trench", and the radially arranged strips *c*² also constitute or form a "trench" and said strips, in the construction shown, are provided with the words "Cross trench" but the circles *d* at the inner ends of the strips *c*² are not a part of these "trenches". The central circular field *b*² bears or contains, in the construction, the word "Citadel" and is also provided with a decorative design or figure but this is not an essential element.

My improved game device also involves two sets of blocks or men, nine in number, and the blocks or men of said sets are differently colored, preferably red and blue, and in Figs. 2 and 3, I have shown, three of each set of blocks or men.

The game is played by two persons, one playing the red and the other the blue, and the player of the red first places one of his men on one of the circles or spots marked 1, 2 or 3 in either of the three outer circles *b*⁴, *b*⁵ and *b*⁶. The player of the blue then places one of his men on another of these circles and so on, alternately, until all the men are played.

The object of each player is to get three men of the same color or side, on the circles or spots next to each other numbered 1, 2, 3 or 3, 2, 1, or 2, 2, 2, and such a series of spots is called a "trench," and whenever a player moves a man onto a circular space or spot which completes a "trench" or series of three spaces or spots, as above, he takes one of his opponent's men off the board, a man cannot be taken from a complete "trench" nor from any of the four spots in the inner or "citadel" circle *b*², these spots or circles being considered and called "safe."

The ultimate object of forming "trenches," as above set out, must be borne in mind when first setting or placing the men at the beginning of the game, and "trenches" formed during this operation count the same as in the playing of the game after the men are placed on the board and a player so forming a "trench" may remove one of his opponent's men from the board. When all the men are set, the playing of the game pro-

ceeds, the red, or the player having the red men making the first move. A move is made by moving a man or block from one spot to another in any direction, but the spot moved to must be a vacant one and next to the spot moved from. A man cannot be moved to a spot already occupied nor can he be jumped over another spot, across from one circle to another can only be made by moving along the cross lines 2, 2, 2 as there are no crossings or cross lines at 1, 1, 1 or 3, 3, 3, and a move must be made along the strip lines c^2 or along the circular lines b^4 , b^5 and b^6 . It is not necessary for a player to form a new "trench" in order to take off one of his opponent's men. This may be accomplished by simply moving one man of three already constituting a "trench" to another position and then moving said man back to the previous position, as this again forms a "trench" and the player may remove one of his opponent's men from the board provided the opponent has not in the meantime occupied the vacant spot by moving one of his own men onto it.

The game is won by one player taking all his opponent's men off the board, or by getting four of his own men in the inner "citadel" circle b^3 entrance to which is made only along the cross lines or strips c^2 having the numerals 2, 2, 2, and moving from one space or spot d to another space or spot in this circle is counted a move the same as in the other circles.

A man cannot be placed in the "citadel" circle b^3 during the process of placing the men on the board at the beginning of the game but only after all of the men have been placed on the board and the movement of the men on the board has begun and a "trench" cannot be formed in the "citadel" circle b^2 .

In the event of a player having only men left in the "citadel" circle he may be forced out of said circle by his opponent moving thereinto and as the other player must move alternately he will be gradually forced out of said circle when his men can be taken off the board in the regular way.

My invention is not limited to the exact design of the diagram on the board herein shown and described, nor to any particular color of the separate sets of blocks or men,

and changes in and modifications of the various details herein shown and described 55 may be made, within the scope of the appended claims, without departing from the spirit of my invention or sacrificing its advantages.

Having fully described my invention, 60 what I claim as new and desire to secure by Letters Patent, is:—

1. In a game device a board provided with a diagram, comprising a central space inclosed by four concentric spaces formed by 65 four concentric lines and divided by four radially arranged lines into equal parts, said radially arranged lines being provided where they intersect the three outer concentric lines with similar numerals and said 70 three outer concentric lines being provided midway between said radial lines with radially arranged and similar numerals.

2. In a game device a board provided with a diagram, comprising a central space 75 inclosed by four concentric spaces formed by four concentric lines and divided by four radially arranged lines into equal parts, said radially arranged lines being provided where they intersect the three outer concentric lines with similar numerals and said 80 three outer concentric lines being provided midway between said radial lines with radially arranged and similar numerals, and two sets of differently designated blocks or 85 men of an equal number each.

3. In a game device, a board provided with a diagram comprising a central circular space inclosed by four concentric spaces formed by four circular lines and divided by 90 four radially arranged lines into equal parts, said radially arranged lines being provided where they intersect the three outer circles with similar numerals and said three outer circles being provided midway between said 95 radial lines with radially arranged and similar numerals.

In testimony that I claim the foregoing as my invention I have signed my name in presence of the subscribing witnesses this 100 10th day of February, 1915.

SYDNEY G. OSBORNE.
